(57) CLAIM

The ornamental design for a portable wheelchair seat saddlebag, as shown and described.

DESCRIPTION

FIG. 1 is a perspective view of a portable wheelchair seat saddlebag showing my new design, shown as it would be in use.

FIG. 2 is a front view thereof, shown flat for ease of illustration.

FIG. 3 is a rear view thereof.

FIG. 4 is a right side view thereof.

FIG. 5 is a left side view thereof.

FIG. 6 is a top plan view thereof; and,

FIG. 7 is a bottom plan view thereof.

The broken line showing of the wheelchair and portions of the article is included for the purpose of illustrating environment and forms no part of the claimed design.
